UNITED STATES PATENT OFFICE

121,082

DESIGN FOR A COMBINED WRENCH HANDLE AND HAIR WINDING PIN

Walter N. Schlesinger, New York, N. Y.

Application January 10, 1940, Serial No. 89,370

Term of patent 3½ years

To all whom it may concern:

Be it known that I, Walter N. Schlesinger, a citizen of Germany, but having declared my intention of becoming a citizen of the United States, and resident of New York city, in the county and State of New York, have invented a new, original, and ornamental Design for a Combined Wrench Handle and Hair Winding Pin, of which the following is a specification, reference being had to the accompanying drawing, forming a part thereof, and of which Figure 1 is a perspective view of a combined wrench handle and hair winding pin with the pin in extended position; Fig. 2

is a front end elevational view; and Fig. 3 is a perspective view thereof taken at right angle of Fig. 1, with the pin in retracted position.

The characteristic features of the design consist in the diminishing annular stepped formation at the small pin end of the tapered shank and in the annular step at the other end of the shank.

I claim:

The ornamental design for a combined wrench handle and hair winding pin, substantially as shown and described.

WALTER N. SCHLESINGER.
